E. FERAD

ICE CREEPER

Filed March 5, 1925

Inventor
Edward Ferad
per *Campbell Umphreys*
Attorney.

UNITED STATES PATENT OFFICE.

EDWARD FERAD, OF NEW YORK, N. Y.

ICE CREEPER.

Application filed March 5, 1925. Serial No. 13,119.

This invention relates to ice creepers.

Among the objects of my invention are to provide a device that may be easily secured to the shoe, one that will fit different sizes of shoes, and one that can be worn over rubbers without injuring them. Other objects of this invention are to provide a device that will be easy on the foot and one that will permit of its use to prevent slipping on icy 10 stairs as well as on level ground.

Referring to the drawings:

Figure 1 is a bottom plan view of a device embodying the principles of my invention.

15 Figure 2 is a view of my device secured in operative position upon a shoe.

Figure 3 is a view in side elevation.

15 Figure 4 is a detailed view of the elongated spikes in the rear plate.

20 In carrying out my invention I propose to provide an ice creeper that is to be secured to the toe and ball portion of the shoe. The ice creeper is formed of thin plates of metal 1, 2, 3 and 4. Plate 1 is the toe plate and has punched therein, holes 10, the punching operation being from the top side to form pronged spikes 11 and holes 10.

25 Towards the rear of plate 1, I provide four channels 12 within which slide bent over ends 13 of clamps 14. Secured to clamps 14 are hooks 15 to which strap 7 is fastened. Strap 7 is preferably made of rubber. Secured to the rear of plate 1 by links 16 is plate 2. A similar plate 3 is likewise secured to plate 2 by links 16. Both these plates have prongs or teeth 17 punched therein similar to those of toe plate 1. Plates 2 and 3 are under the ball of the foot. Plate 4 is likewise connected to plate 3 by links 16. 30 Adjacent the end of plate 4 which is next to plate 3 are spikes 9 which are secured to plate 4 by nuts 18 or in any other well known manner such as by riveting. Plate 4 is shaped like an isosceles trapezoid and 35 fits under the arch of the foot. Secured to the sides of the trapezoid adjacent the rear end are hooks 6 to which are attached strap 8, preferably made of rubber.

In forming the creeper of four plates and

connecting these plates by links permits the 50 wearer to walk on ice more readily since the plate will flex with the sole of the shoe. The large spikes 9 are designed to enable the wearer to more firmly grip the ice should it be necessary.

55 It will also be seen that the adjustability of clamps 14 permits the use of my creeper with various sizes of shoes.

My invention can also be used in connection with high heeled ladies shoes and is 60 likewise adjustable for different sizes. Variations of my device might be made and still fall within the scope of my invention.

What I claim is:

1. An ice creeper comprising a heelless 65 sandal having jointed metallic plates adapted to respectively fit the toe, ball and forward part of the shank portions of the bottom of a shoe, the toe and ballplates having struck out therefrom numerous short prongs distributed over their outer surface to provide a level tread and the shank plate having one or more relatively long rigid spikes disposed thereon in such relation as normally to be in light engagement if any with the 70 ground but adapted to be pressed downwardly when the weight of the body is placed 75 firmly on the arch of the foot.

2. An ice creeper comprising a heelless 80 sandal having flexibly joined metallic plates adapted to fit and flex with the sole of a shoe and means for securing the forward plate to the toe and the rearmost plate up against the shank portion of a shoe forward of the heel, the forward plates having distributed 85 over their outer surface a number of short prongs providing a level tread and the rearmost plate carrying projecting from its outer surface beneath the arch of the foot a transverse row of rigid spikes of such a length 90 as to operatively engage the ground when both the sole and heel of the shoe are in contact therewith and the weight of the body is placed on the arch of the foot.

95 Signed at New York, in the county of New York and State of New York, this 26th day of February A. D. 1925.

EDWARD FERAD.
